M. S. RUNSVOLD & N. NELSSKOG,
AUTOMATIC FIRE EXTINGUISHER SYSTEM.
APPLICATION FILED JULY 22, 1916.

1,270,442.

Patented June 25, 1918.

UNITED STATES PATENT OFFICE.

MARTIN S. RUNSVOLD AND NELS NELSSKOG, OF EVERETT, WASHINGTON.

AUTOMATIC FIRE-EXTINGUISHER SYSTEM.

1,270,442.

Specification of Letters Patent. Patented June 25, 1918.

Application filed July 22, 1916. Serial No. 110,658.

To all whom it may concern:

Be it known that we, MARTIN S. RUNSVOLD and NELS NELSSKOG, citizens of the United States and residents of Everett, in the county of Snohomish and State of Washington, have invented certain new and useful Improvements in Automatic Fire-Extinguisher Systems, of which the following is a full, true, and exact specification.

Our invention relates to improvements in automatic fire extinguisher systems and more particularly to that class of automatic systems which are known as dry pipe systems and has for its principal object to provide a system of the class described in which the pipes of the system do not normally contain either water or air under pressure; to provide improved and novel automatic mechanical means for admitting water under pressure to the system in case of fire; to provide a novel and improved type of valve and valve mechanism for quickly admitting water to the pipes. Another object of our device is to provide novel means for effecting the release of the valve opening mechanism.

Other objects will appear as our invention is more fully explained in the following specification, illustrated in the accompanying drawings and pointed out in the appended claims:

In the drawings Figure 1 is an elevation of our device with parts broken away. Fig. 2 is a plan of a portion of our device showing more particularly the extreme outer end of the system and the automatic valve releasing means. Fig. 3 is an enlarged fragmentary plan of means for effecting the release of the valve mechanism.

Referring more particularly to the drawings, numeral 1 indicates a water main which is connected to a valve 2. The valve 2 is provided with hand opening mechanism and means for retaining a watchman's key so that the key cannot be removed unless the valve is open. An automatic valve 4 is connected adjacent the end of valve 2. Valve 4 embodies a water passage 5 which is normally closed by a valve 6 and a rising screw stem 7 which passes through the nut 8. The nut 8 is suspended by links 9 from levers 10. One end of each of levers 10 is pivoted to the valve body 4 as at 11 while the other end is provided with a roller 12 which normally rests against a cam 13 which is slidably mounted upon stem 7. A cam lever 14 is attached to cam 13 at one end, pivoted as at

15 to a yoke 16 and again pivoted at its outer end to a rod 17. The other end of rod 17 is pivoted to one end of a lever 18 which is fulcrumed as at 19 to a bracket 20. The other end of the lever is provided with a roller 21 which normally rests against the face of a cam lever 22. Cam lever 22 is pivotally mounted at 23 and is provided with a gravity actuated weight 24 at its outer end. 60 A trip 25 is pivoted to the outer end of bracket 20 and engages and retains a dog 26 which is pivoted to cam lever 22 which supports weight 24. Valve 4 is provided with test connections 27 and alarm gage 28 in the usual manner. From the outer end of valve 4 a main 29 leads to small distributing mains 30 which are located conveniently throughout the building which is to be protected. Distributing mains 30 are provided with 70 sprinkler heads 31. A combustible cord or fusible line 32 is attached to trip 25 and holds the said trip normally in an engagement with the dog 26. The line 32 is led along and supported from the mains 29. 75 Where distributing mains branch off from the mains 29 line 32 passes through openings 33 in a pair of shear plates 34 and 35. Shear plate 34 is stationary while shear plate 35 is slidably mounted in a rack 36 and is normally held in position as shown by toggle links 37 which in turn are supported by levers 38 which are pivoted on rack 36. Levers 38 are provided with counter weights 39 and are normally held as shown by means 80 of fusible lines 40 which are held taut along the distributing mains by means of an adjustable spring tightening device 41. In operation when a fire occurs in the vicinity of any of the distributing mains, the fusible line 40 is severed by the heat thus allowing the counter weight 39 to drop down, which in turn operates the shear plate 35 with the result that line 32 is severed. The severing of line 32 releases trip 25, disengages dog 26 85 and allows weight 24 to drop downward. The movement of weight 24 actuates cam lever 22 which acting through lever 18, rod 17 and lever 14 shoves cam lever 13 downwardly between rollers 12. The spreading of rollers 12 straightens out links 9 and raises the nut 8 which pulls the stem 7 with it and thereby raises valve seat 6 and allows the extinguishing fluid to flow through the valves and into the main 29 and the distributing mains 30. From the foregoing, it will be evident that in order to flood the mains

110

it is only necessary to sever either of the lines 32 or 40. Further, the pressure of fluid below valve 6 will instantly open the valve fully when the cam 13 is slightly depressed.

5 While we have shown a particular form of embodiment of our invention, we are aware that many minor changes therein will readily suggest themselves to others skilled in the art without departing from the spirit 10 and scope of the invention, and we therefore desire to avoid being limited to the exact form shown and described.

Having described our invention what we claim as new and desire to protect by Letters Patent, is—

15 1. An automatic fire extinguisher system including pressureless dry pipe mains and distributing mains, an automatically oper-

ated valve, whereby the extinguishing fluid is admitted to the mains, gravity actuated 20 levers, a nut screwed onto the stem of the valve, a cam slidably mounted on said stem and connected to said levers, means coöperating with said cam and connected with said nut, whereby the said nut is raised.

25 2. An automatic dry pipe fire extinguisher system which includes a quick opening valve, a movable valve stem, a nut screwed onto said stem, pivoted levers, links pivoted to the levers and said nut, and a gravity actuated cam mounted on said stem and coöperating with said levers, whereby the levers are moved and the said nut and stem are raised.

MARTIN S. RUNSVOLD.
NELS NELSSKOG.
